(57) **CLAIM**

The ornamental design for a bottle, as shown and described.

DESCRIPTION

FIG. 1 is a perspective view of the bottle.

FIG. 2 is a side view of the bottle shown in FIG. 1.

FIG. 3 is a top view of the bottle shown in FIG. 1; and,

FIG. 4 is a bottom view of the bottle shown in FIG. 1.

The evenly-dashed broken lines shown in the drawings illustrate the portions of the design that form no part of the claim. The dot-dot-dash broken lines in the drawings define the bounds of the claim and form no part thereof. Separated portions of the bottle that are connected by a bracket indicate that any portion of the article between the break lines forms no part of the claimed design.
